UNITED STATES PATENT OFFICE

ALBERT WADLEY KIRKLAND, OF FITZGERALD, GEORGIA, ASSIGNOR TO ATLANTA, BIRMINGHAM AND COAST RAILROAD COMPANY, OF ATLANTA, GEORGIA, A CORPORATION OF GEORGIA

DEVICE FOR DESTROYING WEEDS AND VEGETATION ALONG RIGHT-OF-WAY OF RAILROADS

Application filed January 5, 1929. Serial No. 330,682.

My invention relates to the destruction of weeds and other vegetation along the tracks of railways, including steam railroads. It has for its object to provide improved means for using steam generated in a locomotive of any approved or suitable type and from which superheated steam may be utilized by improved means for killing or destroying the weeds or vegetation.

It also has for its object to provide improved features of construction in the manifold from which the steam in jets or streams is projected against the weeds as the locomotive travels over the railway track.

To the accomplishment of the foregoing and such other objects as may hereinafter appear, the invention consists in the features hereinafter described and then sought to be clearly defined by the claims reference being had to the accompanying drawings forming a part hereof, and in which

Figure 1 is a side elevation of the preferred embodiment of the invention;

Figure 2 is a front end elevation thereof; Figure 3 is a top plan view of the manifold, with a part of the covering plate broken away;

Figure 4 is a front elevation of a portion of the centrally disposed manifold and of one of its hinged sections or wings, and of supporting hangers, with parts in section.

In the drawings, the numeral 1 designates a locomotive of any approved construction equipped with usual steam generating accessories, including a superheater header 2, from which steam will be conducted to the steam distributing manifold as hereinafter described.

Supported from the engine frame and pilot-beam 3 are two parallel beams 4 resting upon the pilot beam and held, say by clips 5, and metal braces 6 secured to the extending beams and to the front of the pilot beam as indicated in Figure 1 of the drawings. The beams 4 are further supported and braced by rods 7 connected at one end to the beams and at the other end to the front of the locomotive as illustrated in Figures 1 and 2. From the beams 4 is suspended the manifold steam distributor which preferably com-

prises a middle or centrally disposed manifold 8 and hinged side wings or auxiliary manifolds 9. The middle or centrally disposed manifold comprises a steam-header pipe 10 having pipes 11 in communication therewith and extending laterally therefrom in opposite directions, said pipes at their outer ends being connected together and braced by metallic plates 12, the pipes 11 having each a series of perforations 13 for the escape of steam supplied to them from the central header pipe 10. This middle or centrally disposed manifold is suspended from the beams 4, in part by a suitable number of metal hangers 14 bolted or otherwise secured at their upper ends to the beams 4 and at their lower ends riveted or welded to the metallic plates 12, which connect together the ends of the laterally extending perforated pipes 11. The wings or auxiliary side manifolds 9 each comprise a header pipe 15 from which extend lateral pipes 16 in communication with the header pipe to receive steam therefrom, and having perforations 17 in the underside for projection of jets or streams of steam from the pipes, the laterally extending pipes being connected together at their outer ends by a metallic connecting plate 18 to which they may be welded or otherwise attached. These side or auxiliary manifolds 9 are supported from the beams 4 by metallic hangers 19 bolted or otherwise attached at their upper ends to the beams 4 and formed with lower U-shaped loop ends 20 in which will loosely lie the header pipe so as to form a hinge connection of the manifold with its hanger support, a bolt 21 joining the hanger and upper end of its loop portions so as to retain the header in its seat. To stiffen or brace the central manifold and contribute to its support from the beams 4, transversely extending metallic strips or bars 22 are provided and secured at their ends by nutted bolts 23 to the hangers 19 and also tied by loops or U-bolts 24 to the header pipe 10 of the central manifold as shown in Figure 4 of the drawings. The transverse bars 22 connected to the central manifold and to the hangers 19 as specified tend to stiffen the manifold and to support it from the beams 100

4 by the hangers 19 as well as by the hangers 14, and thus stability is given to the structure.

The headers 15 of the hinged side wings or auxiliary steam distributors may be provided with valves, say with globe valves 25, for cutting off or regulating the supply of steam to a portion of the header. The header 10 of the central manifold and headers 15 of the side or auxiliary manifolds are connected by nipples 26 with a steam supply pipe 27, the nipples being provided with valves, say, globe valves 28, for cutting off steam from one header or another, and the auxiliary headers 15 are connected with the nipples by a universal joint, say by a ball and socket joint 29, so as to provide for turning of the auxiliary headers in raising and lowering the side manifolds. The lifting and lowering of these side manifolds may be effected by suitable means, for instance, by cables 30 connected at one to the manifolds, and associated with windlasses 31 supported by standards 32 rising from the platform 33 which extends from one beam 4 to the other beam 4. Rods 34 within reach of an operator on platform 33 may extend through keepers 35 and be connected at their lower ends, for instance, by a fork 36, with the valves 28 so as to operate them from the platform 33. The pipe 27 receives steam from the superheater header 2 through pipes 37 which may pass through the housings or boots 38 and through flexible pipes 39 which connect with the ends of the pipe 27, the connection between the pipes 37 and 39 preferably being a ball and socket joint 40, or other form of universal joint, and the pipes 37 may be provided with suitable valves 41 for controlling the passage of superheated steam from the superheater header 2 to the manifolds.

Under the construction described, superheated steam is taken from the superheater header of the locomotive and conducted directly to the headers of the manifold distributors by means of pipes 37 and 39 which have a universal coupling 40 between their meeting ends, thus making it possible to carry super-heated steam from the superheater header of the locomotive direct to the manifold distributors instead of supplying the header of the manifold distributors with steam taken from the valve or steam chest of the locomotive. When the latter is the case as shown in my former Patent No. 1,610,556, December 14, 1926, the steam delivered into the steam chest or valve chest becomes somewhat lowered in temperature due to the exposed surface area of the steam chest and valve chest and the efficiency of the superheated steam to some extent impaired, which is avoided under the present construction. A conventional illustration of an ordinary steam chest 42 and driving piston cylinder 43 is made and the ordinary steam-valve casing or chest omitted because said parts are not

made use of as their functions do not enter into the operation of the present device, and the valve-chest or casing of an ordinary locomotive being omitted and also a portion of the usual housing or boot, which ordinarily increases the steam pipe leading from the steam generator to the valve-chest and steam chest being omitted, the retained portions of the housing or boot are capped as shown. The illustration given indicates that a locomotive engine of ordinary construction may serve for an embodiment of the invention with certain parts not essential to working of the invention omitted.

A canopy or covering 44 of suitable material may be suitably supported above the central and also the side or auxiliary distributing steam manifolds so as to confine to the vegetation to a greater or less degree, the steam issuing from the manifolds. If desired a shelter for the operators of the machine may be provided by a frame consisting of uprights 45 and braces 46 and 47 and cover or roof 48 as illustrated.

The locomotive with its attached steam distributing manifolds will be moved over the rails of the track-way by a locomotive engine of any approved type coupled thereto, and the operators standing upon the platform of the steam distributing attachment by manipulation of the steam-passage controlling valves will direct the quantity of superheated steam deemed necessary for the effective distribution of the weeds and vegetation along the right of way, and whenever found necessary or desirable one or both of the side or auxiliary steam distributing manifolds may be raised or lowered to the extent considered best for the needs existing, and like the steam in the quantity desired may be directed through one or more or all the steam distributing manifolds provided.

While I have illustrated and described the preferred details and relationship of the various parts constituting an embodiment of the invention, changes may be made therein without departing from the essentials sought to be defined by the appended claims.

Having described the invention, and set forth its merits, what I claim is:

1. A device for destroying weeds and vegetation along a railroad right-of-way, comprising a frame supported in front of a locomotive in which steam is generated, steam distributing manifolds supported in suspension from said frame, and comprising a central manifold having a header and side manifolds hinged to said frame and having a header, hangers supported from the frame in front of the locomotive and connected at the lower ends to plates connecting the outer ends of steam distributing pipes projecting from the central manifold header and supporting the central steam distributing manifold, other hangers supported from the frame

in front of the locomotive and supporting the side steam distributing manifolds, said hangers which support the side distributing manifolds having the headers of the side manifolds revolvably supported therefrom, and means for supplying steam from the locomotive to the headers of the several steam distributing manifolds.

2. A device for destroying weeds and vegetation along a railroad right-of-way, comprising a frame supported in front of a locomotive in which steam is generated, steam distributing manifolds supported in suspension from said frame and comprising a central manifold having a header and side manifolds hinged to said frame and having a header, hangers supported from the frame in front of the locomotive and carrying the central steam distributing manifold, hangers supporting the side manifolds from the frame and at their lower ends bent upwardly to form seats in which the headers of the side manifolds are revolvably mounted, members connecting oppositely disposed portions 25 of the side manifold hangers and extending across the headers seated therein to retain the headers in position, and means for supplying steam from the locomotive to the headers of the several steam distributing 30 manifolds.

3. A device for destroying weeds and vegetation along a railroad right-of-way, comprising a frame supported in front of a steam generator, steam distributing manifolds supported in suspension from said frame and comprising a central manifold having a header and side manifolds hinged to said frame and having a header, hangers supported from the frame and carrying the central steam distributing manifold, hangers supporting the side manifolds from the frame and having the headers of the side manifolds revolvably supported thereon, bars 40 extended transversely across and connected 45 with the central manifold and having their ends connected to the hangers which carry the headers of the side manifolds, and means for supplying steam from the steam generator to the central and the side steam distributing manifolds.

In testimony whereof I affix my signature.
ALBERT WADLEY KIRKLAND.
